UNITED STATES PATENT OFFICE.

WILLIAM M. WHITE, OF MILWAUKEE, WISCONSIN.

CENTRIFUGAL PUMP.

Application filed August 20, 1926. Serial No. 130,380.

This invention relates in general to improvements in the construction and operation of rotary hydraulic machines, and relates more specifically to improved protective devices for centrifugal pumps or the like.

An object of the invention is to provide an improved rotary hydraulic machine, such as a centrifugal pump, which is extremely durable in construction. Another object of the invention is to provide pump structure or the like, which is especially adapted to resist destructive action of the liquid passing through the machine. A further object of the invention is to provide new and useful instrumentalities for indicating at the exterior of a hydraulic machine, the defective condition of structural elements at the interior thereof, without interrupting the operation of the machine. Still another object of the invention is to provide simple and efficient means for prolonging the period of usefulness or life of centrifugal pumps or the like. These and other objects of the invention will be apparent from the following description.

A clear conception of an embodiment of the invention and of the mode of operation of devices constructed in accordance therewith, may be had by referring to the drawing accompanying and forming a part of this specification, in which like reference characters designate the same or similar parts in the several views.

Fig. 1 is a central vertical section through an improved multi-stage centrifugal pump which is especially adapted for mine or boiler feed service.

Fig. 2 is a fragmentary enlarged central section through the main shaft and several of the rotors of the improved centrifugal pump.

The centrifugal pump to which the invention has been applied herein by way of illustration, comprises in general a stationary casing consisting of a base section 3 and a top section 4 cooperating with the base section to form a housing, and a plurality of rotors or runners 7 rotatably supported within the housing by means of a main shaft 8. The pump housing is provided with suction and discharge passages 5, 6 respectively, and also has intermediate conduits for conducting the liquid through the successive runners

7 in series. The runners 7 have hubs 23 which embrace and are drivingly connected to the main shaft 8 by means of keys 9, 10, the end key 10 also serving to lock the end-thrust balancing piston 22 to the shaft 8. The keys 9, 10 cooperate with key-ways in the runner hubs 23 and also engage key-ways 11 in the shaft 8, the shaft key-ways being somewhat longer than the adjacent keys thus providing unoccupied spaces at the key ends. The runners 7 are locked against end displacement along the shaft 8, by means of bushings 13 which embrace the shaft 8 between the successive runner hubs 23, and by end clamping sleeves 14 having internal screw threads cooperating with external screw threads 15, 16 formed on the main shaft 8. The spacing sleeves 13 are rotatably disposed within the stationary wearing bushings 12 which are mounted in the main housing, and gaskets 20, 21 may be inserted between the opposite ends of the sleeves 13 and the adjacent ends of the runner hubs 23. The main shaft 8 is provided with a central conduit or bore 17 which communicates with the spaces at the ends of the keys 9, 10 through radial passages 18, and the end of the bore 17 may be provided with a leakage discharge nipple 19, as shown in Fig. 1.

When it is desired to assemble the pump, one of the end keys 9, 10 may first be inserted in the corresponding key-way 11, and the end rotor or runner 7 may be slipped over the shaft and over the positioned key. The gaskets 20, 21, the sleeves 13, and the remaining keys and runners, may then be applied in succession in an obvious manner. When the runners 7, sleeves 13, and gaskets 20, 21 have been properly positioned upon the shaft 8, the clamping sleeves 14 may be applied to the screw threads 15, 16 and adjusted to firmly clamp the elements together in end to end relation. The main shaft 8 with the rotors mounted thereon may then be positioned within the base section 3 of the casing, after which the cover section 4 may be applied to completely enclose the runners 7. It will be apparent that with the pump assembled, the clamping sleeves 14 may be adjusted from the exterior of the housing and without necessity of removing the cover 4. If the gaskets 20, 21 are in good condition, these gaskets provide an effective seal for preventing liquid while pass-

ing through the pump, from entering the spaces surrounding the keys 9. If however one of the gaskets 20, 21 becomes defective, liquid will enter the spaces surrounding the 5 corresponding key 9, 10 and this leakage liquid will flow through the passages 18 to the central bore 17 from whence the leakage liquid will be discharged through the nipple 19. Due to the fact that the keys 9, 10 are 10 snugly fitted only at the sides of the key-ways in the shaft 8 and runner hubs 23, leakage fluid entering these key-ways through the gaskets 21 will flow along the adjacent keys and will likewise enter the 15 spaces 11 and be conducted from these spaces in the manner just described. When delivery of fluid from the nipple 19 occurs, the operator is advised that one or more of the gaskets 20, 21 has become defective and the 20 cover section 4 should then be removed and the defective gasket replaced. Before actually removing the cover section 4, the operator may manipulate one or both of the clamping sleeves 14 in order to ascertain 25 whether or not leakage may be thus eliminated.

From the foregoing description, it will be apparent that the present invention provides simple and efficient means for detecting 30 the defective condition of the gaskets 20, 21 and of avoiding destruction of the keys 9, 10 by acid or other destructive ingredient contained in the liquid being pumped. This indication of the condition 35 of enclosed structural elements is effected during normal operation of the pump and without necessity of removing the cover section 4 of the casing. The passages 18 and bore 17 may be readily applied to the shaft 40 8 at moderate cost, and may if desired be applied to the shafts of existing pumps. While the invention has been described as being specifically applied to a centrifugal pump, it will be apparent that the principles 45 thereof are capable of more general application.

It should be understood that it is not desired to limit the invention to the exact details of construction herein shown and described, for various modifications within the 50 scope of the claims may occur to persons skilled in the art.

It is claimed and desired to secure by Letters Patent:

55 1. In combination, a shaft having a conduit therein, a runner operable by said shaft, and means embracing said shaft and coacting with said runner to prevent displacement thereof along said shaft, said 60 shaft conduit communicating with the joint between said runner and said means and being formed to conduct leakage away from said joint.

65 2. In combination, a shaft having a conduit therein, a runner carried by said shaft,

and a sleeve embracing said shaft and cooperating with an end of said runner to prevent displacement thereof along said shaft, said shaft conduit communicating with the joint between said runner and said sleeve 70 and being formed to drain leakage away from said joint.

3. In combination, a shaft having a central bore and radial passages communicating with said bore, a runner carried by said shaft, and a sleeve embracing said shaft and cooperating with an end of said runner to prevent displacement thereof along said shaft, said radial passages communicating 75 with the joint between said runner and said sleeve and being formed to conduct leakage from said joint to said bore.

4. In combination, a shaft having a conduit and key-ways communicating with said conduit, a runner carried by said shaft at each of said key-ways, and sleeves embracing said shaft and cooperating with the ends of said runners to prevent displacement thereof along said shaft, said shaft conduit communicating through said key-ways with the joints between said runners 90 and said sleeves and being formed to drain leakage away from said joints.

5. In combination, a shaft having a bore and radial passages communicating with said bore, said shaft having key-ways communicating with said passages, a runner carried by said shaft adjacent to each of said key-ways, and sleeves embracing said shaft and cooperating with the ends of said 100 runners to prevent displacement thereof along said shaft, said shaft passages communicating with the joints between said runners and said sleeves through said key-ways and being formed to conduct leakage 105 from said joints to said bore.

6. In combination, a shaft having a conduit therein, a runner carried by said shaft, and means including a sleeve and a gasket embracing said shaft and cooperating with an end of said runner to prevent displacement thereof along said shaft, said shaft conduit communicating with the interior of 110 said gasket and being formed to drain leakage away from the interior of said gasket 115 through said shaft.

7. In combination, a rotary shaft having a central bore therein, a runner rotatable with said shaft, and means including a sleeve and a gasket embracing said shaft and cooperating with an end of said runner to prevent displacement thereof along said shaft, said means being rotatable with said shaft and said bore communicating with the interior of said gasket and being formed 120 to drain leakage away from the interior of said gasket 125.

8. In combination, a rotary shaft having a key-way and a conduit communicating with said key-way, a runner rotatable with 130

said shaft and embracing said key-way, and means including a sleeve and a gasket embracing said shaft and cooperating with an end of said runner to prevent displacement thereof along said shaft, said means being rotatable with said shaft and said shaft conduct communicating with the interior of said gasket and being formed to drain leakage from within said gasket through said key-way. In testimony whereof, the signature of the inventor is affixed hereto. ¹⁰
